FINGER COT

Herbert Spencer Lutz, New York, N.Y., assignor to International Process & Product Development Corporation, a corporation of New York

Filed Feb. 7, 1962, Ser. No. 68,711

Term of patent 14 years

(Cl. D9—2)

FIG. 1

FIG. 2

FIG. 3

FIG. 4

FIG. 5

FIG. 6

FIG. 1 is a front view of a finger cot embodying my new design;

FIG. 2 is a modification of the design shown in FIG. 1;

FIG. 3 is another modification of the design shown in FIG. 1;

FIG. 4 is a view of the back of the design shown in FIG. 1;

FIG. 5 is a side view of the same; and

FIG. 6 is a side elevation thereof shown in open position.

The rear of the modified forms of the design shown in FIGS. 2 and 3 is the same as the rear of the design shown in FIG. 1.

I claim:

The ornamental design for a finger cot, as shown and described.
